UNITED STATES PATENT OFFICE.

NORA S. SMITH, OF HOUSTON HEIGHTS, TEXAS, ASSIGNOR OF ONE-FOURTH TO
J. W. HILL, OF DALLAS, TEXAS.

CRATE.

Specification of Letters Patent.

Patented May 30, 1916.

1,185,441.

Application filed November 9, 1914. Serial No. 871,156.

To all whom it may concern:

Be it known that I, NORA S. SMITH, a citizen of the United States, residing at Houston Heights, in the county of Harris and State Texas, have invented certain new and useful Improvements in Crates, of which the following is a specification.

This invention relates to new and useful improvements in a crate for eggs and the like.

10 The object of the invention is to provide a device of the character described, where-in eggs may be suspended, each in a separate compartment, for shipment.

15 A further feature of the invention resides in the provision of said compartments formed of flexible material and suspended from flexible supports, which absorb the shock, when the crate is moved and lessens 65 the liability of breakage.

20 With the above and other objects in view, the invention has particular relation to certain novel features of construction and arrangement of parts, an example of which 25 is given in this specification and illustrated in the accompanying drawings wherein:—

Figure 1, is a plan view of the crate. Fig. 2, is a sectional side elevation thereof, taken 30 on the line *a—a* of Fig. 1. Fig. 3, is a sectional end view thereof.

35 Referring now more particularly to the drawings, wherein like numerals of reference designate similar parts in each of the figures; the numeral 1, refers to a frame work which may be formed of wood or metal, and which has suitable side and end members united together. The fabric strips 2, are provided, which are formed of cloth or other similar yieldable material secured 40 at their ends to the top and bottom end members of the frame work, by means of the hooks 3. These strips are provided for supports for the egg containers 4. Each container 4, is formed of flexible material 45 preferably fabric, and the containers are arranged in rows between the strips 2, and are secured at their upper and lower ends, respectively, to said strips. These containers form sacks, the upper ends of which are 50 open, each sack being provided to receive

and contain an egg, as shown in Figs. 1 and 2. The open end of each sack is equipped with a draw string, as 5, by means of which the mouth of the sack may be closed and tied.

55 A crate of the character described may be used, not only for the purpose of shipping eggs, but also for use in shipping any other small article which is likely to be injured in shipment.

60 While I have only shown one form of this device, it is obvious that the mechanical structure thereof may be modified without departing from the principle of the invention, and I hereby reserve the right to make 65 changes in the mechanical structure thereof, so long as I keep within the scope of the appended claims.

What I claim is:—

1. A crate including a frame work, strips 70 of fabric forming supports secured to opposite sides of the frame work, containers formed of fabric material, secured to and suspended between said supports each container having an open end to admit an object, and means for closing said open end. 75

2. A crate including a frame work, strips of fabric secured to opposite sides of the frame work, containers formed of fabric secured to and suspended between said strips of fabric, each container having a closed 80 end and an open end to admit an object and a means for closing said open end.

3. A crate including a frame work, strips of fabric forming supports secured to opposite sides of said frame work by means 85 of suitable hooks, fabric containers secured to and suspended between said fabric supports, each container having a closed and an open end, said open end being adapted 90 to admit an object and a means for closing said open end.

In testimony whereof I have signed my name to this specification in the presence of two subscribing witnesses.

NORA S. SMITH.
